UNITED STATES PATENT OFFICE.

HAROLD E. McCREERY AND ALBERT E. JESSER, OF APOLLO, PENNSYLVANIA, ASSIGNEES
TO PITTSBURGH STEEL DRUM COMPANY, OF PITTSBURGH, PENNSYLVANIA, A COR-
PORATION OF DELAWARE.

SHIPPING DRUM.

Original application filed November 20, 1922, Serial No. 602,095. Divided and this application filed
September 26, 1925. Serial No. 58,755.

This invention relates to shipping drums and is a division of our copending application Serial No. 602,095, filed November 20th, 1922, which has matured into Patent 5 No. 1,565,809, dated December 15, 1925.

In our copending application we describe and claim a shipping drum and method of making the same, wherein we provide a substantially cylindrical drum body formed of 10 sheet metal and provided at each end with an inturned flange slightly spaced from and parallel to the body of the drum, a head being adapted for arrangement in each end of the drum and provided with a cylindrical 15 flange turned outwardly toward the end of the drum and adapted to be arranged in the space between the body of the drum and the adjacent inturned flange. A shoulder is rolled inwardly from the body portion to 20 contact with the inner face of each head to properly maintain it in position. In the formation of the drum an interlocking joint is formed at the edges of the metal from which the drum is rolled whereby the edges 25 may be secured together to form a substantially cylindrical body. It has been found advisable to provide the body of the drum with reinforcing beads rolled outwardly therefrom intermediate the heads and when 30 forming the beads it has been found that the edges of the drum are distorted or curved, thus preventing the interlocking joints from being properly brought together. In our copending application above identified, we 35 have also illustrated a drum formed in the manner described and provided adjacent the interlocking joint with reinforcing beads formed integral with the drum and arranged parallel to the interlocking joint. It has 40 been found that when these parallel beads are formed it prevents distortion of the edges of the drum so that the complementary portions of the interlocking joint remain straight, thus facilitating the assembling of 45 the parts.

The present application is directed to the provision of the reinforcing beads referred to and has for its principal object the provision of rolled beads almost entirely surrounding the drum intermediate the heads thereof and longitudinal beads arranged parallel to the edges of the metal from which

the drum is formed to prevent distortion thereof usually due to the formation of the beads surrounding the drum.

Other objects and advantages of the invention will become apparent during the course of the following description.

In the drawings we have shown one form of the invention. In this showing,

Figure 1 is a side elevation of a drum embodying the invention,

Figure 2 is a fragmentary sectional perspective showing the drum assembled,

Figure 3 is a similar view showing the parts disassembled, and,

Figure 4 is a section on line 4—4 of Figure 1.

Referring to the drawings, the numeral 10 designates the body portion of a drum which is formed substantially cylindrical in shape and is provided at opposite edges with longitudinal flanges 11 bent backwardly from each edge to form an interlocking joint, as will be apparent. The drum is provided adjacent each end with an inturned flange 12 which is arranged parallel to the body of the drum and spaced slightly therefrom. A head 13 is adapted to be arranged in each end of the drum and is provided with a peripheral cylindrical flange 14 adapted to be arranged in the space between the body portion and the adjacent flange 12. After the heads are arranged in position, a shoulder 15 may be rolled inwardly from the body of the drum against the inner face of each of the heads to maintain it in position. Each of the flanges 12 may be provided with cut outs 16 to permit contraction of the metal when the flanges 12 are formed. These cut outs are arranged in alinement with each other and spaced from the edges of the flange and after the elements have been assembled, a substantially semi-circular bead 17 may be rolled from the flanges 12 and 14 and the adjacent body portion of the drum. The beads 17 are adapted to form hoops upon which the barrel may be rolled.

In the formation of the drum, substantially circumferential beads 18 are rolled from the metal of the drum as shown in Figures 1, 2 and 3. These beads extend to points slightly spaced from the interlocking

edges of the drum, as shown in Figure 1 and serve as reinforcements to minimize the danger of the drum becoming bent when in use. The body portion of the drum is 5 further provided with longitudinal beads 19 connecting the ends of the beads 18 and the beads 19 are arranged parallel to the interlocking joint at the edges of the drum and extend substantially the entire distance between the shoulders 15.

The operation of the device is as follows: In the formation of the drum, the beads 18 and 19 are rolled or stamped, preferably the latter, while the sheet is flat and the 15 interlocking joint is formed at the edges of the sheet, as will be apparent. Obviously it is necessary that the elements of the interlocking joint be maintained straight in order that the interlocking joint may be brought 20 into proper engagement, as shown in Figure 4. It has been found that where neither of the beads 18 and 19 is provided in the body of the barrel, it is sometimes difficult to bring the elements of the interlocking 25 joint together in proper straight alinement due to the flexibility of the metal. When the reinforcing beads 18 are provided, these elements create a distinct tendency of the 30 elements of the interlocking joint to form a curve, thus making it doubly impossible to properly secure the interlocking joint. It will be obvious that the joint must be substantially perfect in order to present a finished drum which is adapted to contain a 35 liquid since any imperfections in the interlocking joint will cause leakage. We have found that the provision of the longitudinal beads 19 corrects all tendency of the edges of the body to curve or become distorted 40 whereby the elements of the interlocking joint remain straight and may be brought into perfect engagement. After the body of the barrel has been thus assembled the

interlocking joint is rolled against opposite sides to provide a leak-proof joint. 45

It is to be understood that the form of our invention herewith shown and described is to be taken as a preferred example of the same and that various changes in the shape, size and arrangement of parts may be 50 resorted to without departing from the spirit of the invention or the scope of the subjoined claims.

We claim:

1. A drum comprising a metal body formed 55 of a single sheet of material rolled into substantially cylindrical form and having its contiguous edges provided with a locking joint, said body being provided with reinforcing beads arranged substantially at 60 right angles to its contiguous edges and being further provided with stiffening beads on opposite sides of said joint substantially parallel thereto.

2. A drum comprising an integral sheet 65 metal body curved in the form of a cylinder and having its contiguous edges bent back upon themselves to provide an interlocking joint, said body being provided with a reinforcing bead extending throughout the 70 greater portion of its circumference substantially at right angles to said interlocking joint and having its ends terminating a short distance from said joint, said body portion being further provided with reinforcing beads arranged substantially parallel to said joint on opposite sides thereof, said last named beads extending substantially 75 throughout the length of said interlocking joint and intersecting the ends of said first named bead.

In testimony whereof we affix our signatures.

HAROLD E. McCREERY.
ALBERT E. JESSER.
